UNITED STATES PATENT OFFICE.

HERMANN BRUNN, OF MUNICH, GERMANY.

PARALLEL-RULER.

SPECIFICATION forming part of Letters Patent No. 433,976, dated August 12, 1890.

Application filed August 20, 1889. Serial No. 321,372. (No model.)

To all whom it may concern:

Be it known that I, HERMANN BRUNN, of Munich, Bavaria, Germany, have invented an Improved Parallel-Ruler, of which the following is a specification.

My invention consists in the various features of improvement more fully pointed out in the claim.

In the accompanying drawings, Figure I is a top view of my improved parallel-ruler. Fig. II is a cross-section on line $z z$, Fig. I. Fig. III is a similar cross-section showing modifications. Fig. IV is a longitudinal section at the center of the roller b .

To a ruler a a roller b is connected, running in vertical slots c of the bearings d , attached to the ruler. The surface of the roller is slightly roughened, to prevent its slipping upon the smooth paper, and at one end of said roller a graduated ring e is arranged, against which a pointer f , attached to the bearing d , points for the purpose of regulating the distance of the parallel lines to be drawn, as may be desired.

If the ruler is to be arranged to draw a regular fixed distance of parallel lines, the surface of the roller b may be made with regular depressions n and raised parts m , as shown in Fig. III, or cavities k may be made in one end

of the roller b , into which a spring-lever l , attached to the bearing d , works. A slot g' is made in the ruler a , in which a slide g works, capable of being fastened in any position by a screw i . To this slide g a needle-pointed spring h is attached, projecting some little distance over the front edge of the ruler.

When perpendicular lines are to be drawn, the spring h is moved over the point from where the perpendicular line is to begin and the ruler moved toward the top or bottom of the paper, when, by means of the needle-point, an impression is made in the paper, when the perpendicular lines can be drawn by connecting the two points.

What I claim is—

The combination of slotted ruler a with bearings d , and roller b journaled in said bearings, and with slide g , screw i , and needle h , the needle projecting beyond the edge of the ruler, substantially as specified.

In testimony whereof I have signed this specification in the presence of two subscribing witnesses.

HERMANN BRUNN.
